UNITED STATES PATENT OFFICE.

MATTIE D. FORREST, OF MARION, INDIANA, ASSIGNOR OF ONE-HALF TO JOHN H. FORREST, OF MARION, INDIANA.

HOOK AND EYE.

1,418,244.

Specification of Letters Patent. Patented May 30, 1922.

Application filed November 11, 1920. Serial No. 423,395.

To all whom it may concern:

Be it known that I, MATTIE D. FORREST, a citizen of the United States, and a resident of Marion, in the county of Grant and State 5 of Indiana, have invented a new and Improved Hook and Eye, of which the following is a full, clear, and exact description.

This invention relates to improvements in hooks and eyes, an object of the invention 10 being to provide an improved hook and eye which may be quickly attached to adjacent edges of a garment and which are self fastening, in that it is not necessary to sew them to the goods.

15 A further object is to provide a hook and eye formed of spring wire and provided with pins for securing and locking them in a fabric, and to provide improved means in both the hook member and the eye member 20 for accommodating the pins so that there is no danger of pricking the fingers upon operating the hook and eye.

A further object is to provide a device of the character stated which will be simple and 25 practical in construction, neat and attractive in appearance and comparatively inexpensive to manufacture.

With these and other objects in view the invention consists in certain novel features 30 of construction and combination and arrangements of parts as will be more fully hereinafter described and pointed out in the claims.

In the accompanying drawings—

35 Figure 1 is a top plan view of my improved hook and eye attached to the adjacent edges of a garment.

Figure 2 is a view in section through the garment on the line 2—2 of Figure 1.

40 Figure 3 is a perspective view of my improved eye member.

Figure 4 is a similar view of the hook member.

Referring in detail to the drawings, 1 and 45 2 represent the adjacent edges of a garment, and 3 and 4 my improved hook and eye members secured thereto. The hook and eye members are each formed of a single piece of spring wire bent upon itself to give 50 the desired shape.

The intermediate portion of the wire forming the eye member is bent to form a loop 5, the ends of the wire are then flared apart forming shoulders 6. Those portions

of the wire forming the shoulders are 55 slightly offset as shown at 7 to provide grooves or recesses 8 in the shoulders. From the shoulder 6 the ends of the wire extend in parallel directions for a short distance as shown at 9, and are then bent at right angles as shown at 10 and extend inwardly toward each other. The ends of the wire are again bent at right angles and extend in parallel directions back toward the shoulders 6. The extreme ends of the wire are 60 65 pointed forming pins 11 having their pointed ends located under the offset portions 7 in the shoulders 6.

The hook member 3 is formed exactly like the eye member 4, with the exception that 70 the intermediate portion of the wire instead of being located in the same plane with the main body portion of the device is bent at right angles to the plane of the body portion and then bent again at right angles extending for a short distance back toward the body portion in a plane parallel thereto and forming a hook 12 adapted to engage the loop 5 on the eye member. Similar reference numerals have been applied to those 75 80 portions of the hook member 3 which correspond to similar portions of the eye member 4.

In positioning either the hook member or the eye member in a piece of fabric the pins 85 11 are passed through one face of the fabric and extend thereunder for a short distance and then project back through the fabric. By squeezing the free ends of the pins 11 together they may be passed between the 90 shoulders 6 and will spring into the grooves 8 as shown clearly in Figures 1 and 2. The members will thus be securely locked against any accidental displacement or removal from the fabric. 95

Various slight changes and alterations might be made in the general form of the parts described without departing from my invention, hence I do not wish to limit myself to the precise details set forth, but shall 100 consider myself at liberty to make such slight changes and alterations as fairly fall within the spirit and scope of the appended claims.

I claim:

1. A device of the character stated, comprising a hook member and an eye member, each formed of a single piece of wire, the 105

wires forming the members being bent at their intermediate portions to provide engaging hooks and eyes, each of the wires then being flared apart providing shoulders, 5 said shoulders bent to provide keepers, the ends of each wire then extending in parallelism away from the shoulders and including return bends, said wires terminating in parallel pins located between the parallel 10 portions above mentioned, and the free ends

of said pins adapted to be held by the keepers.

2. A device of the character described in claim 1, and in which the pins are held against the shoulders by their own resiliency, and in which said shoulders are spaced a sufficient distance apart to permit the passage of the free ends of the pins therebetween for the purpose specified. 15

MATTIE D. FORREST.
